United States Patent Office

Des. 177,755
Patented May 22, 1956

177,755

RESTAURANT BUILDING

Francis C. Peterson, Erwin, Tenn.

Application November 25, 1955, Serial No. 39,038

Term of patent 14 years

(Cl. D13—1)

FIG. 1

Des. 177,755

PAGE 2

FIG. 2

FIG. 3

Des. 177,755

PAGE 3

FIG. 4

FIG. 5

FIG. 6

Figure 1 is a top plan view of a restaurant building showing my new design;

Figure 2 is a front perspective view looking in the direction of the arrow 2 of Figure 1, and shown on a somewhat enlarged scale;

Figure 3 is a rear elevational view on the scale of Figure 2;

Figure 4 is a perspective view of the restaurant building looking to the right in Figure 2, and shown on a reduced scale;

Figure 5 is a perspective view of the restaurant building looking to the left in Figure 2, and shown on a reduced scale; and

Figure 6 is a cross-sectional view taken along line 6—6 of Figure 2.

I claim:

The ornamental design for a restaurant building, as shown.
